FIN RADIATOR

Austin H. Hart, Long Branch, N. J., assignor, by
mesne assignments, to Heating Appliances and
Equipment Company, Incorporated, a corpora-
tion of Delaware

Application September 8, 1931, Serial No. 561,528

10 Claims. (Cl. 257—124)

My invention relates to a fin type radiator used for house heating purposes and more particularly to improvements in fin construction and assembly.

5 This application is a continuation in part of my copending application, Serial #508,580 filed January 14, 1931, which has now matured into Patent No. 1,935,025 granted Nov. 14, 1933.

The principal object is to construct a fin type 10 radiator, comprising two major parts, a one piece body and a one piece fin member, having a channel formed by slotted openings in the fins, which fin member is adapted to be assembled on the radiator body, by placing same over the top 15 thereof.

Another object is to construct the fin member in such manner that each fin is adapted to tightly grip the radiator body, thereby forming a good metallic contact therewith and retaining a 20 grip which cannot be readily loosened unless force is applied.

Among other features are improved means to properly space said fins and means to assure a good surface contact between the fins and radiator body if the body is cast and has a wavy 25 surface.

By my arrangement the fins are formed from one metallic sheet which has equally spaced 30 openings punched through from one edge, and flanges forming the sides of each opening. After the punching operation the fins are alternately folded, thus forming a sinuous fin structure with a channel at one edge, formed by the aligned punched openings.

35 After the fins are formed they are easily assembled as a unit by placing said unit over the radiator body and forcing same downward to the limit of the openings. Due to slight irregularities in alignment of the slotted openings an excellent 40 clamping engagement is provided between the flanges of said openings and the radiator body.

The preferred form of structure is shown in the accompanying drawings, in which

45 Fig. 1 is a perspective view of a complete radiator assembly with parts broken away to clearly show the body construction.

Fig. 2 is a side elevation of the structure shown in Fig. 1 with a portion broken away.

50 Fig. 3 is a vertical section taken on the line 3—3 of Fig. 2.

Fig. 4 is an enlarged plan view of one end of the radiator assembly.

55 Fig. 5 is a face view of a fin blank as it would look after the stamping and flange forming operation.

Fig. 6 is a section taken along the line 6—6 of Fig. 5.

Figs. 7, 8 and 9 show modified forms of folded fin structure in fragmentary perspective views.

Fig. 10 shows a modified form of fin assembly. 5

Fig. 11 shows a fin with modified form of flange and a reinforcing rib, and

Fig. 12 is a perspective detail view on an enlarged scale showing one portion of a fin and flange. 10

Referring to the drawings in which like reference characters indicate like parts, the reference character 10 refers generally to the radiator body and 12 to the fin structure.

The said body 10 preferably comprises a one 15 piece cast member consisting of a hollow core 14 having a chamber 15, end portions 16—18 formed integrally therewith, and bosses 20—22 at the lower corners. It will be observed that this one piece cast body provides a very rigid structure 20 which requires only the boring and threading of two holes 26—28 for inlet and outlet connections, thus eliminating the time and labor required to assemble end fittings on the core, which is the usual practice in the construction and assembly 25 of fin radiators. Feet 30—32 are formed as a part of the bosses 20—22, which are flat at the bottom for the purpose of supporting the body in an erect position when placed on the floor, and they project below the lower surface of the core 30 to protect said core from sudden shocks when it is moved about, also to provide sufficient metal so that the threaded openings 26—28 may be low enough to permit proper drainage. The walls of the ends 16 and 18 are made somewhat thicker 35 than the core walls to provide shoulders or abutments 34—36. An air valve (not shown) is to be placed in either one of the positions indicated at 38—40, according to the heating system used.

The fin member 12 comprises a continuously 40 folded metallic sheet, folded in alternate or zigzag order, providing a multiplicity of substantially parallel fins 42. Before folding, the sheet is run through a press or other forming machine, which punches openings 44 and forms flanges 45 46—48 at the edges of each opening in alternate directions as indicated in Fig. 5. The openings 44 go through the lower edge of the sheet and when the folding operation of the sheet is completed, said openings are in approximate alignment, thus forming a continuous channel which is adapted to fit over the core 14. The flanges 46 and 48 are bent slightly inward as indicated in Fig. 6 to provide a tight grip when in engagement 50 with the core 14.

Due to slight irregularities in folding operations, the openings will not be in positive alignment although approximately so. This feature however is a decided advantage, since the tortional effect created when forcing the fin structure in place, provides additional gripping power between each fin member and the core, which taken along with the inwardly disposed flanges applies a grip into the sides of said core 14 that cannot be loosened unless force is applied. Also due to this tight grip, a good metallic contact is made which is sufficient to assure adequate heat conduction without resorting to dipping in a galvanizing bath. The latter may be resorted to however if desired. Several staggered projections 50 are formed on each flange 46-48 which engage the wall of the adjacent fin, thereby definitely spacing the fins and preventing the flange of one fin from slipping under the flange of an adjacent fin. It will be observed that these projections are all located in the same relative position as seen in Fig. 5, but when the folds are made, each projection will engage a blank surface of the adjacent fin. Slots 51 may also be provided in the flanges 46-48 to provide further flexibility when the surface of a cast core is wavy.

Another form of fin structure is shown in Fig. 11, in which the flanges 46a have extended portions 70 bent outward at substantially right angles 30 to the flanges 46a, thus providing spacing members which will have a greater bearing surface against the adjacent fin wall than the projections 50, and will provide better heat conduction between fins. A rib 72 may be pressed into the surface of each fin to strengthen same if desired.

While I have shown the fins in the preferred form as applied to a casting and provided with wedge shaped openings, they may be applied to any other suitable form of core and the openings shaped as desired, such as indicated for example, in the structures shown in Figs. 7, 8, 9 and 10. In Fig. 7 the openings 52 form a channel which is adapted to be placed on a core from below; in Fig. 8 a plurality of openings 54 and 56 are shown, 45 which extend inward from both the upper and lower edges; in Fig. 9 the openings 58 are centrally disposed and the entire structure is adapted to surround the core, and in Fig. 10, a two section fin structure 60 and 62 is shown having slots 50 64-66 from one end of each of said sections, and adapted to engage a core 68 from above and below, thereby surrounding same.

Various changes can be made in the details of construction herein shown and described, as 55 forming one embodiment of my invention, any such modifications still being within the scope of the invention here claimed if the principles of operation and results above explained are substantially preserved.

60 I claim:

1. In a radiator fin member a continuously folded metallic sheet having its folds in opposite directions and providing a multiplicity of ver-

tically disposed spaced fins, each fin having a slotted flanged opening from one end thereof, which flanges are adapted to wedge against the sides of a radiator body to become fixed thereto.

2. In a radiator fin member, a continuously folded metallic sheet having its folds in opposite directions and providing a multiplicity of spaced fins, each fin having a flanged opening from one end thereof, and projections formed on said flanges adapted to engage the surface of adjacent fins to function as spacer stops. 5

3. A combination as defined in claim 2 in which the flanges are slotted to provide flexibility when contacting uneven surfaces.

4. In a radiator fin member, a structure as defined in claim 1, in which the slotted openings are formed from below. 15

5. In a radiator fin member, a continuously folded metallic sheet, having its folds in opposite direction and providing a multiplicity of spaced fins, each fin having a substantially centrally disposed opening within it. 20

6. A fin radiator comprising in combination a one piece cast body, having a core with a chamber therethrough, bosses on said body having openings communicating with said chamber and an abutment at each end of said body, and a continuously folded fin member, having slotted openings therein from one end of each fin portion, which fin member is adapted to be placed over said core and grip the sides thereof and the two opposite end fins engage the end abutments. 25

7. In a fin radiator the combination of a one piece cast hollow body member, having bosses cast at the lower ends thereof for inlet and outlet connections, and a raised abutment at each end of said core, with a fin member comprising a continuously folded metallic sheet providing a multiplicity of spaced fins, a slotted opening in each fin from the lower end thereof, having a flange at each side of said slot, said fin member being adapted to be mounted on the core so that the flanges fit against the sides of the core in gripping engagement therewith, and the end fin members abut against the raised abutments. 45

8. In a radiator fin member, a continuously folded metallic sheet, having its folds in opposite directions to provide a multiplicity of fins spaced at substantially equal distances apart, each fin having a slotted opening from above. 50

9. In a radiator fin member, a continuously folded metallic sheet, having its folds in opposite directions to provide a multiplicity of fins spaced at substantially equal distances apart, each fin having slotted openings at opposite ends thereof. 55

10. In a radiator fin member, a continuously folded metallic sheet, having its folds in opposite directions to provide a multiplicity of fins spaced at substantially equal distances apart, each fin having a plurality of slots therein. 60
